Primary Examiner — Deanna L Pratt*Assistant Examiner* — Lilyana Bekic(74) *Attorney, Agent, or Firm* — Peter L. Olson(57) **CLAIM**

The ornamental design for a respirator cartridge, as shown and described.

DESCRIPTION

FIG. 1 is a perspective view showing the new design for a respirator cartridge.

FIG. 2 is a front view thereof;

FIG. 3 is a rear view thereof;

FIG. 4 is a top view thereof, the bottom being a mirror image thereof;

FIG. 5 is a left side view thereof; and,

FIG. 6 is a right side view thereof.

The broken lines in the drawings illustrate portions of the respirator cartridge which form no part of the claimed design.
